[57] CLAIM

The ornamental design for a tray top for a food service tray, as shown and described.

DESCRIPTION

FIG. 1 is a top plan view of a tray top for a food service tray showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a cross-sectional view taken along the line 6—6 of FIG. 1;

FIG. 7 is a cross-sectional view taken along the line 7—7 of FIG. 1;

FIG. 8 is a cross-sectional view taken along the line 8—8 of FIG. 1;

FIG. 9 is a cross-sectional view taken along the line 9—9 of FIG. 1; and,

FIG. 10 is a cross-sectional view taken along the line 10—10 of FIG. 1.

The broken line showing of the lower portion of the food service tray is for illustrative purposes and forms no part of the claimed design.
